LINING FOR OIL BURNER BASES

Frank M. Golon, Springfield, Mass.

Application December 27, 1932
Serial No. 649,001

4 Claims. (Cl. 158—87)

My invention relates to improvements in linings for oil burner bases.

An object of my invention is to provide a removable lining for oil burner bases, in which the wicks for the burner are supported, and are designed, in such a manner as to retain within the lining all of the carbon deposited during the combustion of the liquid fuel in the burner.

At present, all of the burners in use deposit carbon directly onto the various surfaces of the base member of the burner, and it becomes necessary, from time to time, to remove or clean out this deposit. When the burner is installed in a range, steam boiler, furnace, or other heating apparatus, such a cleaning process is an extremely awkward and difficult one, requiring the services of an experienced person. Even under very favorable conditions, it is practically impossible to remove, or clean out, all of the carbon, without dismantling the whole burner and removing the base member from the heating apparatus. It is the purpose of this invention to provide a lining which will catch all of the deposited carbon, and which may be quickly and easily removed from the burner, taken to a convenient place for cleaning, and as easily returned to its position in the burner base.

Another object of the invention is to provide such a lining and of such economical material and construction, that when desired, the lining may be removed and thrown away, and replaced by a new lining.

These and other objects and advantages of my invention will be more fully described in the specification, the accompanying drawings, and the appended claims.

An embodiment of my invention is illustrated in the accompanying drawings, but I do not confine myself to this exact construction, as it will be readily understood by all those skilled in the art that my invention may be adapted for use in any type, or construction, of oil burner base.

In the drawings:—

Fig. 1 is a cross sectional view of a typical base portion of an oil burner, in which the annular fuel grooves and connecting passageways are open at the top, with my lining and wicks in place.

Fig. 2 is a plan view of a lining, removed from the base and adapted for use in the base, illustrated in Fig. 1.

Fig. 3 is a partial, cross sectional view, showing a modified construction of the lining at the connection of the fuel feed pipe to the burner base.

Fig. 4 is a view similar to Fig. 3, showing another modified form.

Fig. 5 is a view similar to Fig. 3, showing still another modification.

Fig. 6 is a partial, sectional view similar to Fig. 1, in which the burner base is formed with covered passageways connecting the fuel grooves. 60

Fig. 7 is a sectional view on the line 7—7 of Fig. 6.

Fig. 8 is a plan view similar to Fig. 2, showing the separate lining members used in the base, illustrated in Fig. 6, in proper relative position, 65 and

Figs. 9, 10, and 11 are perspective views of connecting members in co-operation with the lining rings, illustrated in Fig. 8.

Referring now to the drawings in detail, in 70 which like numerals refer to like parts throughout:—

The base member 1 is formed with the concentric walls 3, 4, and 5, forming the concentric annular oil grooves 6 and 7, and the wall 8, forming the oil-receiving bowl 9. The bowl 9 and groove 7 are connected by a plurality of U-shaped passageways, or bridges 10, and the oil groove 7 is connected to the oil groove 6 by similar passageways 11, the passageways 10 and 11 being 80 formed as an integral part of the base member 1. The bowl 9 is formed with the opening 12 in which is fitted the fuel supply pipe 13. The removable lining member 15, (see Fig. 2) is designed to conform to the shape of the base with 85 which it is to be used, such as the base 1, and is made to fit closely against the various surfaces of the base member with which it comes in contact. The removable lining member 15 is formed with the outer oil-receiving U-shaped groove 16, 90 the inner U-shaped oil-receiving groove 17, as shown in Fig. 2, the central bowl 18, and the connecting U-shaped grooves 19 and 20. The floor 21 of the bowl 18 is formed with the depression 22, at the bottom of which is the raised annular 95 rim 23. Wicks 24 and 25 are removably supported in the U-shaped annular grooves 16 and 17. Thus, the wicks 24 and 25 may be assembled conveniently and correctly in the removable lining 15, before it is placed in the burner base. 100 This is an important feature, as it eliminates the necessity of reaching into the narrow confines of the combustion chamber of a kitchen range, or steam boiler, to remove and replace burned out wicks. Because of the awkward conditions existing around the usual installation of an oil burner, the wicks, when renewed with the burner in place, are often misplaced in the annular grooves of the base member, resulting in distortion, spreading, and ragged edges, and therefore, 110

inefficient operation. By the use of my invention, the lining 15 may be removed from the burner, the wicks accurately positioned, and the lining returned to the burner base with the wicks in place. The raised annular rim 23, in the depression 22, serves to catch any carbon which tends to enter the pipe 13, thus preventing any clogging of this pipe.

Figs. 3, 4, and 5 illustrate typical modifications of the construction of the removable lining 15, at the entrance of the fuel supply pipe 13. In Fig. 3, the pipe 13 projects above the inner surface 1' of the burner base 1, and the floor 21 of the bowl 18 of the lining 15 is formed with an upwardly extending flange 26 around the opening 22, which fits snugly around the fuel pipe 13. In Fig. 4, the floor 21 is flat and formed with an opening 27, approximately equal to the inside diameter of the pipe 13. In Fig. 5, the floor 21 is formed with the downwardly extending flange 28, which fits within the pipe 13.

Figs. 6 to 11, inclusive, illustrate a modified form of lining designed for use with that type of burner which has a base formed with covered connecting passageways between the oil grooves and the fuel-receiving basin. The base 1'' is similar to the base 1, except that the passages 10' and 11' are formed with the roof portions 30 and 31. The lining 32 is composed, in combination, of the separate annular oil groove members 33 and 34, the connecting and locking members 35, and the fuel-receiving bowl 36. The lining 32 is installed in the base 1'', by first dropping the members 33, 34, and 36 into the grooves 7', 6', and bowl 9', respectively, of the base, then inserting the members 35 in the passages 10' and 11'. To remove the lining, the action is reversed. The members 35 are comparatively longer than the passages 10' and 11', and lap over the members 33, 34, and 36, thus holding them down and preventing oil from getting under them and floating them. The members 35 may be U-shaped, as illustrated in Fig. 9, square tubular, as shown in Fig. 10, and cylindrical, as shown in Fig. 11, or any other shape necessary to conform to the particular type of burner with which the lining is to be used. Also, the shape of the lining members 15 and 32, and the relative arrangement of their various parts may be varied to fit any burner base. The location of the fuel entrance opening 22 may be located in the bowl 18, the oil grooves

16 or 17, or passages 19 or 20, as indicated at 22' in Fig. 2, depending upon the design of the burner base to be fitted.

It is to be understood that the removable linings 15 and 32 are composed of any suitable material, as iron, steel, or any alloy that will stand high temperatures, without breaking down.

What I claim is:—

1. In an oil burner base having an annular fuel groove, a fuel-receiving basin, and a passage between the groove and the basin, a removable lining member having an annular fuel groove, a fuel-receiving basin, and a passage between the groove and the basin being so disposed as to fit snugly within the burner base for preventing contact of the fuel oil and the surfaces of the burner base. 85

2. In an oil burner having a base member formed with a plurality of annular oil grooves and connecting passages between the oil grooves, and a fuel supply pipe connected to the base member, a thin metal lining so formed as to conform in shape to all the inner surfaces of said base member and removably supported in said base member, said lining also having an outwardly extending nipple formed with an opening and extending into said fuel supply pipe. 95

3. In combination, with the base of an oil burner having a plurality of oil grooves and a fuel-receiving basin and a plurality of passages connecting the oil grooves and the fuel basin, separate lining members conforming in shape to said oil grooves and said fuel-receiving basin and removably secured therein, wicks removably secured in the lining members in said oil grooves, 110 separate passage lining members removably secured in said passages and overlapping the lining members in said oil grooves and said fuel-receiving basin, and means for introducing fuel oil into the lining member in said fuel-receiving 115 basin. 105

4. In an oil burner having a base member including inner and outer grooves and a fuel receiving bowl, a plurality of radially disposed open-topped fuel passages affording communication between the inner and outer grooves and bowl, a lining conforming in shape to said grooves, passages and bowl, and removably engaged therein, and means for introducing fuel oil through the base member into the lining. 120
